UNITED STATES PATENT OFFICE

ZENZO ISHIKAWA, OF YOKOHAMA, JAPAN

WATERLESS GAS HOLDER

Application filed August 31, 1928. Serial No. 303,288.

This invention relates to improvements in gas holders, especially those provided with a disc-like closure member.

In a waterless gas holder with a disc-shaped closure member guided by rollers disposed vertically and rolling along the inner surface of the wall of the gas holder, the distance between the upper and the lower guide rollers cannot be very much increased owing to the fact that it inevitably lessens the available height of the reservoir. Consequently the closure member is liable to tilt, leading to the leakage of gas.

The present invention aims to obviate this drawback, and provides a closing device of a very good stability and reliability.

According to my invention the closure member is disc-shaped, or preferably dish-shaped, adapted to contain a certain quantity of ballasting liquid therein, and has a ballasting weight disposed at the centre thereof, all composed in such a manner that the centre of gravity of the entire movable system is situated at a certain appreciable distance vertically downwardly of the centre of the buoyancy resulting from the total upward pressure of the gas, which fact enables the closure member to assume the equilibrium position of its own accord, and insures a very reliable guiding thereof.

In a practical embodiment of the invention, the closure member is formed to a flat circular receptacle or container, the bottom of which is shaped in an inverted shallow cone, at the centre of which is attached a housing to accommodate ballasting weights and also means to regulate the amount of the ballasting liquid in the receptacle is provided in the housing.

The invention also comprises a novel means of sealing with the aid of a sealing liquid, such as oil, to effectively prevent the least possible leakage along the periphery of the disc-shaped closure member.

In the accompanying drawings, which show one embodiment of the invention:

Figure 1 is a vertical longitudinal sectional view through a gas holder provided with a closure member according to my invention, parts being shown in elevation,

Figure 2 is an enlarged vertical sectional view of the closure member,

Figure 3 is an enlarged vertical sectional view of the sealing device,

Figure 4 is an enlarged longitudinal sectional view of the telescopic conducting device of the sealing liquid, and

Figure 5 is an enlarged fragmentary longitudinal section taken through the line V—V of Figure 2.

Referring more particularly to the numerals of reference on the drawings, 1 is a gas holder or reservoir, preferably of the cylindrical type, supported by the truss structure 2. 3 is a disc-like closing member movable vertically in the gas holder 1. This closure member 3 is formed like a shallow vessel, open upwardly, with the lateral wall 4 and the bottom wall 5 shaped like an inverted funnel and reinforced by annular ribs 6. Centrally of the bottom 5 and depending therefrom is a housing or chamber 7 for accommodating weights 8 of any suitable material, such as cast iron or lead, calculated approximately to give the predetermined pressure to the gas in the reservoir 1.

With an object of varying the gas pressure and enabling an accurate adjustment thereof, the disc-like closure member 3 is adapted to hold a certain amount of ballasting liquid

9. To regulate the amount of the liquid, a valve 10 is provided over the top portion of the housing 7, controllable with the aid of the handle 11 associated with the valve rod 12 (Figures 2 and 5). When the valve 10 is opened, a portion of water in the member 3 flows into the exit tube 13 through the port 14, and then to the interior of the housing 7, going out of it through the overflow holes 15 and falling onto the bottom of the reservoir and collecting to the pool 16, to be finally led to the well 17 through the underground pipe 18.

Outside of and along the lateral wall 4 of the closing member 3 is secured through the intermediary of channel-iron 20 a wooden block 19 which serves to guide the vertical motion of the closure member 3. A packing piece 21, which may be made of any suitable material such as felt, jute or leather for ex-

ample, is securely held at a portion thereof by being pinched between the wooden block 19 and a web portion of the channel 20, the remaining portion of the packing piece is allowed to extend over the inner surface of the wall of the gas holder 1, being held straight by a supporting member, such as angle iron 22. The downwardly depending portion of the lower one of the two packing pieces 21 will tend to flare outwardly and stick to the wall of the gas holder due to the pressure of the gas acting on it, which fact further insures a very close sealing. It is preferable that two of the sealing devices such as just described be disposed one over the other. The free space 23 left over the uppermost sealing device and lying between the wall of the gas holder and the lateral wall of the closure member constitutes an annular channel for the sealing liquid.

The sealing liquid, which may be oil or any other suitable liquid such as gas-tar, is supplied to the supply pipe 24 provided outside of the gas holder. The pipe 24 is held rigid by bars 33 secured to the roof, as shown in Figs. 1 and 4. This pipe 24 is connected within the roof of the truss work to the top of a combination oil pipe 25 consisting of component pipes of varying diameters and sliding telescopically one within the other. This telescopic oil conduit opens at a small tube 26 attached to the lowermost end thereof to a short sleeve 27, which is in turn connected at the bottom thereof to a plurality of radially disposed small pipes 28 ending at a horizontal nozzle 29, from which oil flows in jets, producing an annular body of the sealing liquid along the channel 23.

By means of the sealing device above described the least possible leakage of gas in the reservoir is avoided. The oil that oozes out of the lowermost packing piece flows down along the wall of the gas holder and collects in the annular channel 30, from which the used oil may be pumped out, properly cleaned and heated, if desired, and may again be circulated through the sealing system.

As the closure disc 3 goes up and down in the gas holder, the combination pipe 25 will contract and dilate like a telescope and yet insures a perfect joint. When the closure disc comes to its lowermost position, it will ride over the seats 31 provided along the periphery of the bottom of the reservoir. If desired, the closure disc 3 may be provided with a circumferential platform 32 for the sake of inspection.

As above described the disc-shaped closure device according to my invention, floating on a volume of gas with its centre of gravity far underneath the centre of buoyancy, is very stable and is guided in a very reliable manner, and the sealing means insures a perfect sealing, the least conceivable leakage of the gas being avoided.

What I claim is:

In a waterless gas holder, a movable closure member having sealing means arranged along its periphery, said closure member shaped so as to form a container adapted to hold a ballasting liquid therein and provided with a funnel-shaped bottom, said bottom having a chamber extending downward from its central portion, solid weights in said chamber, and controlling means to regulate the quantity of the ballasting liquid in said container.

In testimony whereof I affix my signature.

ZENZO ISHIKAWA.
